WINDOW CONSTRUCTION

Earl F. Gaines and Walter C. Lippert,

Milwaukee, Wis.

Application March 2, 1943, Serial No. 477,726

2 Claims. (Cl. 20—44)

This invention relates to windows of the general class shown and described in U. S. Letters Patent No. 2,217,543, issued to us on the 8th day of October, 1940, the present invention being an improvement thereon.

The object of the invention is to provide a double hung window, the upper and lower sashes of which may be swung laterally to open position at any point in the length of the window frame or casing, thereby providing a sliding sash window possessing all of the advantages of an inwardly swinging casement window.

A further object of the invention is to provide a double hung window having interengaging sleeve hinge members secured to the upper and lower sashes thereof and so constructed as to permit vertical movement of the sashes as well as inward swinging movement thereof.

A further object is to provide means at the free end of each sash and coacting with the window frame or casing for holding the sashes against swinging movement and, at the same time, provide a weather-tight joint between the parts.

A further object is to provide a manually operable cam for releasing the spring pressed weather strip at the free ends of the sashes so as to permit the sashes to be swung laterally to open position when desired, and yieldable means associated with the cam for automatically seating the weather strip when the cam is released.

A further object is to offset the inner portion of the outer sleeve hinge member with respect to the window casing so as to permit inward swinging movement of the upper sash without disturbing the lower sash.

A still further object of the invention is generally to improve this class of devices so as to increase their utility, durability and efficiency.

In the accompanying drawings:

Figure 1 is a front elevation, partly in section, of a double hung window embodying the present invention.

Figure 2 is a transverse sectional view, taken on the line 2—2 of Figure 1.

Figure 3 is a vertical sectional view taken on the line 3—3 of Figure 1.

Figure 4 is a detail perspective view, partly in section, of one side of the window frame, showing the manner of securing the sleeve hinge members in position thereon.

Figure 5 is a transverse sectional view.

Figure 6 is a perspective view of a portion of one of the outer sleeve hinge members.

Figure 7 is a similar view of a portion of the inner sleeve hinge member of the upper sash.

Figure 8 is a similar view of the sleeve hinge member of the lower sash.

Figure 9 is a detail perspective view of a portion of the upper sash and the adjacent portion of the window casing, showing the weather strip connection between the parts.

Figure 10 is a vertical sectional view of Figure 9.

Figure 11 is a transverse sectional view, taken on the line 11—11 of Figure 10.

Figure 12 is a detail perspective view of the operating cam and its associated parts.

Figure 13 is a transverse sectional view illustrating a modified form of the invention.

The improved double hung window forming the subject matter of the present invention comprises a frame or casing 5 having weight compartments 6 and provided with upper and lower sashes 7 and 8, said sashes being mounted for vertical sliding movement within the casing and so constructed as to permit the sashes to be swung inwardly to open position when desired.

Secured to the frame or casing 5 and extending the entire height thereof, are outer hinge members 9, preferably formed of sheet metal and including angularly disposed portions 10 and 11, the metal at the ends of said portions being curled or rolled to form tubular members or sleeves 12 and 13. One of these hinge members is secured to each side of the casing by screws or similar fastening devices 14, with the portion 11 thereof extending within the casing and disposed at substantially right angles to the portion 10, as best shown in Figure 5 of the drawings.

Secured to the vertical stiles of the lower sash 8 by screws 15, is a companion hinge member 16 having a terminal sleeve 17 which fits within the

sleeve 12 of the adjacent hinge member so as to permit sliding movement of the lower sash thereon and also to permit said lower sash to be swung laterally to open position when desired. Secured to the inner face of the frame of the upper

sash 7 is a filler strip 18 and fitting over said filler strip and secured thereto and to the upper sash, by a suitable fastening device 19, is an upper hinge member 20 provided with a terminal sleeve 21 which fits within the sleeve 13 in the adjacent outer hinge member 9 and thus permits the upper sash to be adjusted vertically within the window frame and also to swing laterally to open position. Extending through the interengaging sleeves and operatively connected with the upper and lower sashes, are window cords

22 which extend over suitable pulleys 23 mounted in the frame and thence downwardly within the compartment 6 for attachment to suitable weights 24. The sleeves 13 of the outer hinge members 9 are offset with respect to the sleeves 12 thereof so as to permit the upper sash to be swung inwardly to open position without interfering with the lower sash, the rear edge of the upper sash being cut away at 25 to permit swinging movement of the upper sash without binding or wedging action between the parts. While the outer hinge members 9 extend the entire height of the window frame, the members 16 and 20 preferably only extend the height of the upper and lower sashes respectively.

As a means for holding the upper and lower sashes against inward swinging movement and to insure a weather-tight contact with the window frame, there is provided for each sash, a weather strip assembly of the construction best shown in Figures 9 to 12 inclusive of the drawings. This assembly comprises a vertically disposed substantially U-shaped member or strip 26 extending the entire height of each sash and provided with laterally extending flanges 27, the portion 26 being adapted to fit within a seating groove 28 formed in the adjacent face of the window frame. Extending laterally from one side of each U-shaped member 26 is an arm 29 having a terminal angular lip 30 which coacts with a cam 31 for the purpose of releasing the U-shaped member 26 from within the groove 28 when it is desired to swing the adjacent sash inwardly, as will be more fully explained hereinafter. Each sash is provided with a longitudinal recess 32 and seated in each recess is a metal casing 33 having outwardly bowed springs 34 attached thereto and which serve to normally and yieldably hold the member 26 within the seating groove so as to insure a weather-tight joint between the parts. When the member 26 is in extended position, the flanges 27 will bear against the adjacent portion of the casing 33 and limit the inward movement of said member. Two cams 31 are preferably provided for each window sash, each cam being secured to a stub shaft 34 journaled in the adjacent window sash, and each stub shaft being provided with a terminal slot 35 adapted to receive a suitable tool for turning the cam. Extending laterally from each recess 32 and communicating therewith, is an auxiliary recess 36 which serves to receive the adjacent cam 31 and to permit longitudinal movement of the arm 29 when the cam is rotated.

It will thus be seen that, under ordinary conditions, the upper and lower sashes may be adjusted vertically of the window frame to any desired position and in which event the sleeve hinges act as guides, it being understood, of course, that there will be sufficient clearance between the U-shaped member 26 and the groove 28 to permit vertical sliding movement of the sashes while, at the same time, insuring a good weather-tight contact with the window frame. When it is desired to swing either the upper or lower sash inwardly to open position, a suitable tool is inserted in the slot 35 of the adjacent stub shaft 34 and the cam 31 carried thereby rotated so as to retract the U-shaped member against the tension of the bowed springs 34 and thus release said U-shaped member from the groove 28 so that either sash is free to swing laterally to open position with the sleeve hinges as pivots. By rotating the cams 31 in the reverse direction, the springs 34 will automatically

cause the U-shaped members or strips 26 to seat within the adjacent grooves 28 and thereby hold the sashes against swinging movement and, at the same time, insure a weather-tight contact between the parts. While both sashes may be slid vertically at any time and each is mounted for swinging movement, it will be understood that the inner sash must be swung inwardly to the position indicated by dotted lines of Figures 3 and 5 before the outer sash 7 can be swung inwardly to the position shown in Figure 5.

5 The construction of the sleeve hinge members and their attachment to the sashes is such that either sash may be swung inwardly to open position so that the window may be used in the same manner as an inwardly swinging casement window. If desired, a suitable packing 36' may be seated in the window frame and the groove 28 formed in said packing in order to assist in providing a weather-tight connection.

10 In Figure 13 of the drawings, there is illustrated a modified form of the invention designed to reinforce and strengthen the side stiles of the sashes. In this form of the device, one of the 15 vertical stiles of each sash is reinforced and strengthened by the provision of a metallic casing 37 and slidably mounted within said casing is a hollow actuating member 38 which receives the cam 39, said actuating member being provided 20 with terminal hook portions 40 adapted to engage suitable lips 41 carried by the U-shaped member or strip 42, there being bowed springs 43 disposed within the casing 37 for causing the U-shaped strip 42 to yieldably engage the groove 30 in the casing when the cam 39 is moved to released position. In this form of the device, when the cam is rotated, the hooks 40, by engagement with the lips 41, will retract the U-shaped strip 42 against the tension of the springs 43 and, when the cam is moved to released position, the 25 springs 43 will cause the strip 42 to automatically seat within the groove in the casing, as will be readily understood.

20 While the sleeve hinge mounting and weather strip assembly is particularly designed for use on windows of wood construction, it will, of course, be understood that the device may be used with equally good results on a metal window. It will also be understood that the device may be made in different sizes and shapes and constructed of any suitable material without departing from the spirit of the invention.

45 Having thus described the invention, what is claimed is:

50 1. In window construction, a frame, upper and lower sashes mounted within the frame, an outer hinge member secured vertically along a side of the frame and extending the entire height thereof, said hinge member being provided with leaves disposed at right angles to each other and each leaf having a sleeve extending vertically and open along one side, other hinge members secured to side edge portions of the upper and lower sashes at the said side of the frame and provided with vertically extending sleeve portions fitting within companion sleeve portions of the first hinge member whereby to permit either sash to be swung laterally to open position, and means for holding the sashes in closed position.

55 2. In window construction, a frame, upper and lower sashes slidably mounted in the frame, one of said sashes provided with a beveled portion and the other with a cut away portion, a filling strip secured to the forward face of the beveled

sash at said cut away portion, an outer hinge member secured to the frame and provided with angularly disposed portions formed with sleeves extending the entire height of the frame, one of said angular portions fitting within said cut away portion, inner hinge members having sleeve portions fitting within the first mentioned sleeve portions, one of said inner hinge members fitting over the filling strip, sash cords extending

5 through the sleeve portions for engagement with weights, and means for normally holding the sash members in position for vertical sliding movement within the frame, said sash members being movable laterally to open position with the sleeves as a pivot when the holding means is released.

EARL F. GAINES.
